PAPER CAN BODY

Alexander G. Hatch, Rochester, N. Y., assignor to
 Fibre Can Development Corporation, Rutland,
 Vt., a corporation of Vermont

Application November 7, 1936, Serial No. 109,625

9 Claims. (Cl. 229—5.5)

It has been heretofore proposed to make a paper can body by preparing a blank of different uniform widths and rolling said blank upon a mandrel into tubular or cylindrical form with the narrower portion of the blank in contact with the mandrel so as to form a shoulder within the tubular member in spaced relation to the ends thereof, upon which shoulder the ends of the can may seat and be held. In such can bodies, to provide a shoulder of adequate width the paper stock from which the can body is formed must be relatively thick where a single convolution or thickness is relied upon to provide the shoulder; and where the stock is relatively thin a plurality of convolutions or thicknesses must be rolled in order to provide a supporting shoulder of sufficient width. Practice and experience has determined that the width of the supporting shoulder must be at least 0.03 of an inch wide. Hence, where paper stock of say 0.01 of an inch thickness is employed it has been heretofore customary and necessary to have at least three overlying convolutions or thicknesses to provide a satisfactory shoulder.

My present invention contemplates the provision of can end supporting shoulders of desired width with the use of considerably less paper stock than is now deemed to be necessary. The preferred manner in which I propose to accomplish this is by doubling back upon itself the marginal portion of all or a part of the paper stock which heretofore has been used to provide the shoulder portion of proper width. In other words, where heretofore two overlying convolutions of paper were necessary to provide a suitable shoulder, I now use a single convolution, the marginal portions of which are doubled back upon the body of the paper. In an analogous manner, where the paper stock is very thin, the marginal portions of one or more of the convolutions may be doubled back to provide additional thickness at the shoulders. The invention will be better understood from the detailed description which follows when considered in conjunction with the appended drawing wherein I have shown several embodiments of my invention and wherein:

Figure 1 is a diametrical section through a paper can body showing one embodiment of my invention;

Figs. 2, 3 and 4 are fractional diametrical sections through paper can bodies showing modifications of my invention;

Fig. 5 is a fractional plan view of a blank for forming a can body such as shown in Fig. 4;

Fig. 6 is a fractional plan view of a blank for forming a can body such as shown in Fig. 2.

Fig. 7 is a fractional plan view of a blank for forming a can body such as shown in Fig. 3.

Referring to the drawing, the various can body sections disclosed therein are of the type formed by rolling a paper blank upon a cylindrical or other polygonally shaped mandrel to provide a tubular casing having an internal shoulder at least one end and preferably at both ends, against which shoulder or shoulders the ends of the can may seat and be secured. The paper stock from which these can bodies are made is preferably first treated to render it impervious to the substance which the can is intended to hold, or in other words, treated to render it water-proof if the can is intended to hold liquid contents dissolved in water, or treated to render it oil or grease proof if the can is intended to hold lubricating oil, grease or the like.

In Fig. 1 the can body is shown as being of tubular form and containing three overlying convolutions or thicknesses of paper, the inner two, 10 and 11, of which are of a height less than that of the outer convolution 12, so as to terminate in spaced relation to ends of the outer convolution 12 to provide internal shoulders 13 and 14 against which a can end such as at 15, is adapted to seat and be held by a beaded over end of the outer convolution 12, as indicated at 16. To increase the width of the shoulders 13 and 14 without employing any additional paper stock than has heretofore been used in the making of a can of this type, I double back upon itself the marginal portion of at least one of the inner convolutions 10 or 11, so as to provide an additional thickness of material 13' and 14'. The height of these doubled back portions 13' and 14' may be the same as the distance that the shoulders 13 and 14 extend inwardly from the top and bottom of the convolution 12 respectively, so that said doubled back portions may be cut directly from the blank from which the outer convolution 12 is formed without increasing the width of the material used therefor. A blank suitable for this purpose is shown in Fig. 7, and has a maximum uniform width 17 equal to the height of the can body and a minor uniform width 18 corresponding to the height of the inner convolutions of the can body which provide the shoulders. The length of the portion 17 of greater width is equal to at least that required to provide one convolution of a can body of required diameter while the portion of lesser width 18 as herein shown is equal to at least twice the length required to

provide a can of proper diameter; or in other words, the portion of width 18 is sufficient to provide overlying convolutions or thicknesses for such can body. A part of this portion 18 of 5 lesser width, is of a length 19 to provide one convolution of the can body, and is formed with an initial width equal to the normal width 17 of the blank, with its marginal portions 18' of a width equal to the length of the can body above 10 the shoulder doubled back upon the portion 19 to provide marginal portions of double thickness. The can body shown in Fig. 1 is formed from the blank shown in Fig. 7 by rolling the narrow end of the blank upon a cylindrical mandrel with the 15 doubled back portions in contact with the mandrel. Of course, the doubled back portions, as well as the body of the blank, will be adhesively secured to the body of the blank which it overlies.

20 The can body shown in Fig. 3 is analogous to that shown in Fig. 1, and primarily differs therefrom in that the folded back portion 13" in the formation of the can body is disposed outwardly of the mandrel so that in the winding of the can body the doubled back portions 18' will be disposed toward the outer convolutions of the can body.

The can body shown in Fig. 2 is also analogous to that shown in Fig. 3 and primarily differs therefrom in that instead of the can body being formed with two convolutions of lesser width, it has but a single convolution 10' of lesser width. Such can body can be suitably rolled from a blank such as shown in Fig. 6, which consists of 35 a portion of greater uniform width 20 and a portion of lesser uniform width 21, each being of a length substantially equal to the circumference of the can body to be formed therefrom. The portion of lesser width 21, it will be noted, 40 has its marginal portions of double thickness at 21' formed by doubling back upon the body a width of material equal to the distance between the marginal edges of the portion of lesser width and the edges of the portion of greater width.

45 In the embodiment of the invention shown in Fig. 4, the can body has the general form of that shown in Figs. 1 and 3 and primarily differs therefrom in that the intermediate convolution 11 of the can body is the one provided with a folded back marginal portion 11' to provide the 50 shoulder of increased width adjacent the top of the can body. This embodiment of the invention may conveniently be formed from a blank such as shown in Fig. 5, which consists of a 55 portion of uniform width 22 and portions 23 and 24 of lesser but uniform width, the portion 23 being intermediate the portions 22 and 24 and being formed with doubled back marginal portions 23' of a character and width quite similar 60 to those heretofore described with respect to portions 18' and 21'. In rolling the blank of Fig. 5 upon a mandrel the top face of the portion 24 as viewed in the drawing is brought into contacting relation with the mandrel and the portion 65 23 is caused to overlie the portion 24 so that the doubled back portions 23' will engage the back of the portion 24.

70 Where the paper stock from which the can body is to be formed has a thickness of say about 0.01 of an inch, at least three such thicknesses are required to provide a suitable can end supporting shoulder. It will be seen, however, from the foregoing description that such three thicknesses at the shoulder portion of the 75 can body can be provided from but a double

thickness of the can body proper. Where the thickness of this paper stock is say 0.015 of an inch thick, a single inner convolution of the can body with doubled back marginal portions will provide a shoulder portion of 0.03 of an inch 5 thickness. Where the paper stock is very thin, say about 0.004 or 0.005 of an inch thick, a greater number of convolutions will be required, but one or more of these may have its marginal portions doubled back and thus reduce by one or more the total number of convolutions required. Where the paper stock is relatively thick and may give rise to slight buckling at the doubled back marginal portions during the rolling of the blank, the doubled back portions may be formed 10 with notches 25 spaced longitudinally of said doubled back marginal portions, and of a depth slightly less than the width of said doubled back portions as shown in Fig. 5. These notches will facilitate a smooth rolling of the doubled back 15 portion without detracting from the effective width of the resulting shoulders formed thereby.

In the commercial production of can bodies of the type contemplated by the present invention it will be apparent that the blanks such as 20 shown in Figs. 5, 6 and 7 may be cut from paper stock to provide marginal portions which may be doubled back upon the body of the blank in the course of feeding the blank to the mandrel for rolling the can bodies. I do not herein show 25 any specific mechanism for accomplishing this, since the present invention is directed to the can body and method of making same and not to the machine for making such can bodies.

30 From the foregoing detailed description it will be apparent that I have disclosed several forms 35 of paper can bodies with end supporting shoulders of suitable width and the method of making such can bodies, by using less paper stock than has been heretofore required in the fabrication 40 of such can bodies, and without materially adding to the operative steps necessary to the fabrication thereof, and while I have shown and described several embodiments of my invention, I 45 do not wish to be limited to the specific forms illustrated, since it will be apparent to those skilled in the art that these various embodiments may be deviated from without departing from the spirit of the invention as defined in the appended claims.

50 What I claim is:

1. A tubular paper can body comprising a single blank of paper stock formed into an inner shell and an outer shell, with the inner shell in juxtaposition to the outer shell and secured thereto, said inner shell having at least one of its ends inwardly spaced from the adjacent end of the outer shell to provide a shoulder within said outer shell and said shoulder being provided, at least in part, by an outwardly folded back marginal portion of the blank from which the inner shell is formed.

2. A tubular paper can body comprising a single blank of paper stock formed into an inner shell and an outer shell, with the inner shell in juxtaposition to the outer shell and secured thereto, said inner shell having at least one of its ends inwardly spaced from the adjacent end of the outer shell to provide a shoulder within said outer shell and said shoulder being provided, at least in part, by a folded back marginal portion of the blank from which the inner shell is formed, said folded back portion being folded outwardly with respect to the inner wall of the can body.

3. A tubular paper can body formed from a single blank of paper stock wound upon itself to provide a can body having a plurality of convolutions or thicknesses greater than two with at least two of said convolutions terminating at one end in inwardly spaced relation to the other convolution, to provide a shoulder, and said shoulder having an effective width greater than the combined thicknesses of the convolutions providing the shoulder by having at least one of said last mentioned convolutions formed at said shouldered end with its marginal portion bent back upon itself.

4. A tubular paper can body formed from a single blank of paper stock wound upon itself to provide a can body having a plurality of convolutions or thicknesses greater than two, with at least two of the innermost convolutions terminating at one end in inwardly spaced relation to the other convolution, to provide a shoulder, and at least one of said innermost convolutions being formed at said shouldered end with its marginal portion bent outwardly back upon itself.

5. A blank for a tubular paper can body consisting of a sheet of paper having adjacent longitudinal portions of different uniform widths, each portion being of a length to provide at least one convolution of a tubular can body of given diameter, and the portion of lesser width having its marginal portion for at least part of its length of double thickness formed by folding a portion of the paper of greater width back upon itself.

6. A blank according to claim 5 wherein the portion of the blank which is bent back upon itself is of a length to provide at least one convolution of the can body.

7. The method of forming a tubular paper

can body which comprises forming a sheet paper blank with adjacent longitudinal portions thereof of different uniform widths, each portion being of a length to provide at least one convolution of a tubular can body of given diameter, the portion of lesser width being formed at least in part by folding back upon that portion of the sheet the part constituting the marginal difference in the width of the two portions and winding said blank on a mandrel.

8. The method of forming a tubular paper can body which comprises forming a sheet paper blank with adjacent longitudinal portions thereof of different uniform widths, each portion being of a length to provide at least one convolution of a tubular can body of given diameter, the portion of lesser width being formed at least in part by folding back upon that portion of the sheet the part constituting the marginal difference in the width of the two portions and winding said blank on a mandrel, beginning with the portion of lesser width.

9. The method of forming a tubular paper can body which comprises forming a sheet paper blank with adjacent longitudinal portions thereof of different uniform widths, each portion being of a length to provide at least one convolution of a tubular can body of given diameter, the portion of lesser width being formed at least in part by notching the edges at spaced distances apart for a portion of the length of the sheet of greater width and folding said notched part back upon that portion of the sheet to provide at least a portion of the sheet of lesser width and winding said blank on a mandrel, beginning with the portion of lesser width.

ALEXANDER G. HATCH.
